UNITED STATES PATENT OFFICE.

FRED W. BAUER, OF MILWAUKEE, WISCONSIN.

MATTRESS OR THE LIKE.

Application filed January 19, 1921. Serial No. 438,478.

To all whom it may concern:

Be it known that I, FRED W. BAUER, a citizen of the United States, residing at Milwaukee, county of Milwaukee, and State of Wisconsin, have invented new and useful Improvements in Mattresses or the like, of which the following is a specification.

This invention relates to mattresses or the like. It is particularly directed to an improved means of securing the springs of resilient mattresses and cushions in position.

Objects of this invention are to provide a novel means for securing the springs to the covers of resilient mattresses or cushions and to provide novel means of securing adjacent springs to each other.

Further objects are to provide for simultaneously securing adjacent springs to each other and to the covering; to provide means for securing such springs by widely spaced portions of the same securing member; to provide a novel means of distributing the strain placed upon the securing means; and to so organize the securing means that any slack resulting from the manipulation thereof may be taken up at each successive spring; and to generally simplify the construction of resilient cushions such as mattresses, upholstery and the like.

Embodiments of the invention are shown in the accompanying drawings, in which:

Fig. 1 is a partial plan view of a mattress embodying one form of the invention with parts of the covering broken away to illustrate details of the construction.

Fig. 2 is a fragmentary side elevation of the structure shown in Fig. 1.

Fig. 3 is a view corresponding to Fig. 1 showing a further form of the invention.

Fig. 4 is an enlarged detail of the final knot for each spring.

Fig. 5 is an enlarged detail of one of the intermediate knots.

This invention relates to either a mattress such as shown in Fig. 1 or an automobile cushion such as shown in Fig. 3. It is to be noted that as a rule lighter springs are used in mattress construction than in automobile seats or other similar resilient cushions. Where heavier springs are used, additional securing means are usually employed as illustrated in Fig. 3.

In practicing this invention, the springs

are arranged in a series of rows as illustrated in either Fig. 1 or Fig. 3 and a covering of burlap or similar material is spread over the upper surface thereof with the edges hanging down upon the sides of the springs. This covering is then tucked in between each of the springs as indicated at 1 in Fig. 2, thereby spacing adjacent portions of the terminal convolutions of the springs apart by the interposed double thickness of fabric. After the covering has been thus arranged, the stitching is begun at one corner of the mattress and continued around the four sides thereof across the upper ends of the outer rows of the springs. Thereafter, the stitching may continue roughly as a spiral or else back and forth across the length or the width of the mattress. The stitching is begun by passing the needle thru the fabric and under the outer portion of the upper convolution of a corner coil and is thereafter knotted. From this point, the stitching extends around a rectangle about the upper end of this coil and at each place where it is attached it passes thru the burlap and under the terminal convolution and is knotted as indicated in Fig. 5. When the stitching has passed completely around the terminal convolution, it is passed diagonally across the coil and knotted. From this point, the stitching follows the rectangular outline indicated in Fig. 1, passing thru the burlap and knotted at the four points of the next coil. The final knot, however, is formed as in Fig. 4 by passing the securing cord downwardly thru the burlap about both terminal convolutions and under the adjacent strands of the securing coil for the first spring. It will thus be seen that this final knot serves as a means to take up any slack resulting in the securing cord of the first coil. This method of stitching is continued around the entire mattress as stated above.

After one covering is in place, the partially formed mattress is turned upside down and the other covering is positioned and stitched as was the first one. After these two coverings are in position, their side margins are stitched together, for example, by folding them inwardly as indicated at 2 in Fig. 2, and running a line of stitching 3, such for example, as ordinary machine stitching, completely around the sides of a mattress.

2

Fig. 1 shows one form of the invention and the securing of one or more springs will be described in detail. The burlap covering is indicated at 4 and adjacent springs at 5, 6, 7 and 8. The securing cord 9 is knotted about adjacent portions of the terminal convolutions of the springs 5 and 6 passing downwardly thru the burlap within each of the convolutions and thru the folded portion 1 of such covering. After the knot, similar to that indicated in Fig. 5 has been formed, the cord 10 is passed along one side of a rectangle thru the burlap and about the outer portion of the terminal convolution 15 of the spring 6 and knotted in the same manner. The cord 11 is now passed from this point along the second side of the rectangle thru the burlap and knotted about the terminal convolutions of the springs 6 and 7 20 passing thru the folded portion 1 of the burlap. From this point, the cord 12 passes along the third side of the rectangle thru the burlap and the folded portion thereof about the terminal convolutions of the 25 springs 6 and 13, is knotted and passed back to the starting point 14 along the fourth side of the rectangle, this length of cord being indicated at 15. This knot is, however, formed differently from the knots previously described. It is, of course, to be understood that the portions 9, 10, 11, 12, 15, etc. of the cord are integral, that is to say, the cord runs continuously from the starting point completely around the mattress and across all the spring terminal convolutions upon one side of the mattress.

The last mentioned knot is illustrated in Fig. 4 and it will be noted that the securing cord 15, along the last side of the square, is passed downwardly thru the burlap inside of the terminal convolution of the spring 5, thru the folded portion 1 of the burlap, upwardly thru the burlap about the terminal convolution of the spring 6, over the securing cord 10, under the securing cords 16, 9 and 17 of the spring 5, above the burlap covering, and either over or under the cord 15 of the spring 6. When this cord 18 is then tightened, it takes up the slack in the cords 16, 9 and 17 of the spring 5.

From this point, the cord 18 extends diagonally across the terminal convolution of the spring 6 and is knotted as indicated in Fig. 5, downwardly thru the burlap, thru the folded portion thereof, and upwardly so as to pass about the terminal convolutions of the springs 6 and 7. It is now knotted as indicated at Fig. 5 and the process is repeated. If the mattress be considered as made of successive concentric closed series of springs, each series arranged in rectangles, the cord 18 passes diagonally across all of the springs except the corner springs of each series. At the corner springs, the same method of stitching is employed except after

the final knot, as indicated in Fig. 4, is formed, the cord 19 passes parallel to the cord 20 of the spring 7 and to the knot 21 which secures the terminal convolutions of the coils 7 and 8 together. From this point, the stitching proceeds as described for the spring 6.

In assembling the springs prior to the positioning of the first covering thereon they may conveniently be placed upon a series of pegs carried by a jig or templet to hold them in proper arrangement. However, after the stitching of the first covering has been finished, the springs are securely positioned in their proper relation to each other and the covering and spring forming the partially finished mattress may be turned upside down upon a flat surface and the second covering applied and secured. It is to be noted that by running a line of stitching, completely around the outer rows of springs that all of the springs are more firmly positioned and the subsequent stitching of the inner springs is more readily effected.

This method may be advantageously employed for mattresses or resilient cushions of any type in which springs formed of medium sized resilient wire are employed. However, when springs of relatively heavy wire are employed, as for example, in automobile cushions, additional stitching may be made over this stitching already formed.

Fig. 3 is a fragmentary view of an automobile cushion formed of relatively heavy springs 22, 23, 24, etc. After the burlap covering has been properly positioned and secured as previously described by the first form of stitching, a second stitching is made by passing a cord 25 directly along one row of springs. This cord 25 is knotted at 26 about the terminal convolutions of springs 24 and 27, passes diagonally as indicated at 28 across the spring 24, and is knotted as indicated at 29 about the terminal convolutions of springs 23 and 24, the cord in each case, of course, passing downwardly thru the burlap, thru the folded portion 1, and upwardly, as is obvious from an inspection of Figs. 2 and 3. This line of stitching continues until the margin of the mattress is reached. At this point, the knot 30 is formed and the cord is passed as indicated at 31 to the knot 32 for the spring 23. From this point, the cord passes as indicated at 34 along the next row of springs. This process is repeated until the entire rows of springs have been secured by this transverse line of stitching. Similar longitudinal lines of stitching as indicated at 35 are formed and pass longitudinally along parallel rows of springs as indicated in Fig. 3.

After one side of the automobile cushion or other resilient cushion has been stitched

as indicated in Fig. 3, the cushion is reversed and the process repeated upon the other side thereof.

It will be noted that this additional series 5 of transverse and longitudinal stitching gives additional security against breaking strains such as are often encountered in automobile cushions. However, the first form of stitching also contributes to the ultimate 10 strength and secure positioning of the springs and cooperates with the transverse and lateral stitching just described to produce an extremely strong and efficient cushion.

15 In addition to the forms of stitching shown in Figs. 1 and 3, this invention contemplates employing the reenforcing stitching such as shown at 25 and 35, Fig. 3, alone. In this case, an additional line of stitching 20 would be run completely around the marginal edges of the terminal convolutions prior to the formation of the longitudinal and transverse stitching such as indicated at 25 and 35. This marginal stitching would pass 25 thru the burlap and be knotted about the outer portions of each of the terminal convolutions completely around the periphery of the mattress.

It will be seen that a very simple method 30 has been provided for securing adjacent springs to each other and to the fabric covering of resilient mattresses or similar articles. It will also be seen that the article produced has very desirable characteristics, such as a 35 small number of parts and equalization of strains in the connecting cord and a great inherent strength thereby successively resisting displacement of its various parts and stresses imposed thereon.

40 It will further be seen that in practicing this invention, the stitches, knots, and peculiar relation thereof, produces a mattress of great inherent rigidity and strength. The final knot, following the stitching of each 45 spring to the covers, takes up the slack in all of the cords passing across the top of that spring and serves to tie the adjacent springs very tightly together. This is particularly desirable in a mattress or cushion of this 50 type. A mattress constructed in this manner will stand alone without bowing over or otherwise folding. It is not necessary to provide an external or surrounding framework for a mattress made in this manner as 55 its initial shape will be retained independently of any auxiliary supporting means.

I claim:

1. A resilient cushion comprising covering members, a series of rows of helical springs interposed between said covering members, a flexible member for each of the covers stitched thru the corresponding cover and knotted around a terminal convolution at a plurality of points, and a knot formed 65 by said flexible securing means and around

adjacent attached portions thereof to take up slack in the attached portions of said flexible securing means, said flexible securing means extending from said last mentioned knot to the next terminal convolutions throughout the entire series. 70

2. A resilient cushion comprising flexible covering members, a series of rows of helical springs interposed between said covering members and having terminal convolutions adjacent such covering members, securing means comprising a flexible member for each of the covering members stitched through the appropriate covering member and around adjacent convolutions of successive springs at a number of widely spaced points and knotted at each point, said securing means having a final knot for each spring, said knot having a portion passing beneath a plurality of strands of the covering member and adapted to draw outwardly against such strands and thereby take up the slack in the said strands, whereby an extremely rigid, firm, resilient cushion is produced. 80

3. In a resilient cushion, the combination with a pair of spaced covering members; of a plurality of helical springs disposed between said covering members, said springs having upper and lower terminal convolutions; and a cord for each of said covering members, said cords being arranged upon their respective covering members in a series of rectangles, each rectangle being disposed above a terminal convolution and having its corners passed through its adjacent covering member and about said terminal convolution and an adjacent terminal convolution. 90

4. In a resilient cushion, the combination with a pair of spaced covering members; of a plurality of helical springs disposed between said covering members, said springs having upper and lower terminal convolutions; and a cord for each of said covering members, said cords being arranged upon their respective covering members in a series of rectangles, each rectangle being disposed above a terminal convolution and having its corners passed through its adjacent covering member and about said terminal convolution and an adjacent terminal convolution, said cords being arranged in certain of said rectangles to provide a diagonal cord having its ends knotted about adjacent terminal convolutions and side members of said rectangles, whereby said terminal convolutions may be secured together and the sides of said rectangles may be pulled taut. 105

5. In a resilient cushion, the combination with a pair of spaced covering members; of a plurality of helical springs disposed between said covering members, said springs having upper and lower terminal convolutions; and cords for each of said covering 110

115

120

125

130

members, said cords being arranged upon their respective covering members to form a series of rectangles having their corners passed through the covering members and 5 about the terminal convolutions and said cords being arranged also to form a pair of diagonals for each of said rectangles, said diagonals having their ends passed through their respective coverings and about adjacent 10 cent terminal convolutions to form a knot, whereby said terminal convolutions may be secured together.

6. A cushion structure including spaced covers, series of springs between said covers 15 with their terminal convolutions in contact therewith and closely adjacent to each other, and a flexible cord passed in a turn around one of said convolutions and through the adjacent cover at four points peripherally 20 spaced about said convolution, each of said turns being inclusive of an abutting point on a convolution of an adjacent spring.

7. A cushion structure including spaced covers, series of springs between said covers 25 with their terminal convolutions in contact therewith and closely adjacent to each other, and a flexible cord passed in a turn around one of said convolutions and through the adjacent cover at four points peripherally 30 spaced about said convolution, each of said turns being inclusive of an abutting point on a convolution of an adjacent spring, said cord being disposed above said convolution in a closed four sided figure and extended 35 diagonally across said figure to the convolution of an adjacent spring.

8. A cushion structure including spaced covers, series of springs between said covers 40 with their terminal convolutions closely adjacent to each other, and a flexible cord passed consecutively across a plurality of successive convolutions, said cord being disposed in a plurality of chords about the periphery of each convolution and engaged 45 in a turn about the convolution and through the adjacent cover at each end of each such chord.

9. A cushion structure including a plurality of series of springs with their terminal 50 convolutions closely adjacent upper and lower spring covers, and a flexible cord passing consecutively across a plurality of successive convolutions and disposed in a plurality of chords about the periphery of each convolution and engaged in a turn about the said 55 convolution and through the adjacent cover at the end of each chord, one of said turns

comprising a knot and the cord being extending thence on a chord of said convolution to a new convolution of the series. 60

10. A cushion structure including a plurality of series of springs with their terminal convolutions closely adjacent upper and lower spring covers, and a flexible cord passing consecutively across a plurality of successive convolutions and disposed in a plurality of chords about the periphery of each convolution and engaged in a turn about the said convolution and abutting convolutions of adjacent springs and through the adjacent cover 70 at the end of each chord, one of said turns comprising a knot and the cord being extended thence on a chord of said convolution to a new convolution of the series. 75

11. A cushion structure including spaced covers, series of springs between said covers with their terminal convolutions closely adjacent, and a cord passing consecutively across a plurality of successive convolutions, said cord being knotted to one convolution, 80 extended across a first chord thereof and passing in a turn about the convolution and portions of the adjacent cover, thence across a second chord substantially at right angles to the first and in a turn as aforesaid, thence across a third chord substantially parallel to the first and in a turn as aforesaid, thence across a fourth chord to the point of beginning and in a turn as aforesaid, and thence diagonally across the closed figure thus 85 formed to a point of beginning on a new convolution of the series. 90

12. A cushion structure including spaced covers, series of springs between said covers 95 with their terminal convolutions closely adjacent, and a cord passing consecutively across a plurality of successive convolutions, said cord being knotted to one convolution, extended across a first chord thereof and passing in a turn about the convolution and portions of the adjacent cover, thence across a second chord substantially at right angles to the first and in a turn as aforesaid, thence across a third chord substantially parallel to the first and in a turn as aforesaid, thence across a fourth chord to the point of beginning, and in a turn as aforesaid, and thence diagonally across the closed figure thus 100 formed to a point of beginning on a new convolution of the series, said turns including adjacent portions of the convolutions of 105 abutting coils. 110

FRED W. BAUER.
